FLOWER POT HOLDER

Marie C. Cimo, New Orleans, La.

Application July 26, 1955, Serial No. 37,131

Term of patent 7 years

(Cl. D33—3)

Fig. 1

I claim:

The ornamental design for a flower pot holder, as shown.
